UNITED STATES PATENT OFFICE.

MICHAEL LIPTAK, OF ST. PAUL, MINNESOTA, ASSIGNOR TO A. P. GREEN FIRE BRICK COMPANY, OF MEXICO, MISSOURI, A CORPORATION OF MISSOURI.

FURNACE WALL.

Application filed April 8, 1922. Serial No. 550,841.

To all whom it may concern:

Be it known that I, MICHAEL LIPTAK, a citizen of the United States, residing at St. Paul, in the county of Ramsey and State of Minnesota, have invented certain new and useful Improvements in Furnace Walls; and I do hereby declare the following to be a full, clear, and exact description of the invention, such as will enable others skilled in the art to which it appertains to make and use the same.

My present invention relates to furnace wall structures and is in the nature of an improved modification or refinement of the wall structure disclosed and broadly claimed in my pending application Serial Number 521,376, filed December 10, 1921. The present improved wall has all of the advantages of the wall of said pending application and certain other important features, all as will hereinafter clearly appear. Generally stated, the invention consists of the novel construction and arrangement of parts hereinafter described and defined in the claims.

In the accompanying drawings, which illustrate the invention, like characters indicate like parts throughout the several views.

Referring to the drawings:

Fig. 1 is a fragmentary perspective showing the improved wall with certain of the blocks removed;

Fig. 2 is an elevation looking at the inner face of the permanent outer wall of the complete wall structure;

Fig. 3 is a fragmentary vertical section of the wall, some of the blocks being shown in full, for the purpose of clearness;

Figs. 4, 5, 6 and 7 are perspective views of certain of the blocks of the wall structure; and

Fig. 8 is a view corresponding to Fig. 1, but illustrating a construction of a somewhat modified form.

The complete wall structure, when designed for an outside wall, is made up of what may be designated as a permanent masonry outer wall and a replaceable high refractory masonry inner wall. In the preferred construction, the permanent outer wall, throughout that portion that is subjected to the most intense heat, is faced with higher refractory bricks or blocks, which become a permanent part of said outer wall structure. As a highly important feature, fire tiles or high refractory blocks, desig-

nated as "sill" blocks, are built into the permanent wall along certain horizontal lines; short pilasters are built on or between the inner portions of the sills thus formed, and these pilasters are capped by so-called lintels, thereby forming between the pilasters rectangular pockets. The fire bricks forming the inner facing of the permanent outer wall are laid in courses on the lintels and completely fill the spaces between the lintels and the inner portions of the overlying sills. In the preferred construction, the sill-forming blocks and the lintels have approximately the same vertical thickness as standard bricks.

The outer common bricks 9 of this permanent outer wall may be laid in any desired number of horizontal layers, but, as shown in the drawings, Figs. 1, 2 and 3, are laid in a width of two bricks throughout that portion that is faced with the fire bricks. The above noted sill-forming blocks are indicated by the numeral 10, the pilaster-forming bricks by the numeral 11 and the lintels by the numeral 12. The rectangular pockets formed in the fire brick or tile facing 9^a of the permanent outer wall are indicated by the numeral 13, and these, it will be noted, are horizontally twice as long as the pilasters are wide. Preferably and as shown, the pockets 13 are the height of three bricks which form each pilaster, but, of course, these dimensions may be varied. At the bottoms of the pockets, the upper surfaces of the sill blocks 10 are preferably formed with raised ledges 10^a that extend about half-way to the backs of the pockets.

The replaceable inner wall should be made up entirely of higher refractory bricks or tiles, and this replaceable inner wall is made up chiefly of horizontal belts of fire bricks 14, but between these belts 14 are interposed horizontal layers of shelf-forming blocks or tiles 15 that constitute an important feature of this invention. These shelf tiles 15 preferably have the same cross-section as a commercial brick, but are enough longer than an ordinary brick to reach the backs of the pockets 13 and to project a full brick length inward of the inner face of the permanent outer wall. Of course, the cross-sectional dimensions of these shelf-forming blocks may be varied, at will, but in the arrangement illustrated, four of the same are required to horizontally fill each pocket 110.

13. At their inner ends, said blocks 16 are provided with depending ledges 15^a, which engage the sill-forming blocks 10 inwardly of their ledges 10^a and positively interlock 6 said blocks 15 and 10 when the former are held downward. To hold the blocks 15 thus interlocked, key-blocks or bricks 16 are employed. These key-blocks 16 are preferably commercial fire bricks, slightly tapered 10 and arranged to fit and fill the space between the tops of the blocks 15 and the immediately overlying lintels 12. When these keys are applied, they positively hold downward the inner ends of the shelf-forming 15 blocks 15 in interlocked engagement with the sills and cause the said blocks 15 to form cantilever projections or shelves. Preferably, fire clay 17 is placed in the slightly diverging space between the lintels and the 20 underlapped portions of the key-blocks 16. The key-blocks or bricks 16 project beyond the lintels but not to the ends of the blocks 15. At places where the pilasters 11 are found, there will be, primarily, spaces between 25 the groups of shelf-forming blocks 15, but these spaces may be filled with ordinary fire brick, which, under the action of heat, soon become fused and held in position, even if the underlying bricks 14 30 should be removed. Fire bricks 18 are laid in a layer immediately on the uncovered end portions of the shelf blocks 15 and spanning the gaps between the groups thereof, and the fire bricks 14, which form the so-called 35 horizontal belts, are laid directly on the bricks 18 and on the projecting ends of the key-blocks 16.

In the modified construction illustrated in Fig. 8, the sill-forming blocks 10^b, instead 40 of forming a continuous sill, are spaced and the pilasters 11^a are made deeper and extended down between blocks 10^b. Also, the lintels 12^a and the pockets 13^a are made deeper than in the construction illustrated 45 in Figs. 1, 2 and 3. Moreover, the shelf-forming blocks 15^c are made of such width that, horizontally, they fill the pockets 13^a. Also, the lintels 12^a overlying the pockets are beveled so that they fit the taper of the 50 key-blocks or bricks 16^a, thereby obviating the use of clay or filling material. As the blocks 15^c are made much thicker vertically than commercial bricks, supplemental shelf-forming tiles 19 are laid between the projecting 55 portions of the blocks 15^c. In both of the constructions illustrated, the upper portion of the permanent outer wall where the heat is not so intense, is, except for the sill blocks and lintels, made up of commercial 60 or common brick.

It will, of course, be understood that in the first construction of the complete wall the permanent outer wall and replaceable inner wall will advisably be progressively 65 built up together, although it would be pos-

sible and practicable first to completely build the outer wall and then to completely build up the replaceable inner wall. In either event, however, the shelf-forming tiles or blocks 15 or 15^c, as the case may be, would at no time be called upon to completely carry an overlying load, although they at all times interlock the two walls together and prevent lateral separation thereof. In the use of the furnace, the blocks and tiles of the inner wall will soon become fused together so that the mass is thoroughly interlocked. By the time repairs are necessary, the inner wall will be considerably burned away so that even when a complete belt of bricks 14 are removed the load on the overlying shelf-forming blocks will have been greatly reduced. Nevertheless, these shelf-forming blocks or tiles would carry the full load of complete blocks if, at any time, this becomes necessary in making repairs. Hence, they will, at all times, support the load of masonry or brickwork 14 above any particular shelf. Repairs will always be made before any of the bricks of the permanent outer wall are damaged, but the shelf-forming tiles or blocks will, of course, have to be replaced, and this may be easily done simply by removing the key-blocks so as to loosen up the damaged shelf-forming blocks. The pilasters between the pockets always give the permanent wall a complete support that is the full width thereof, so that there is never any danger of the permanent outer wall toppling over, even if made thin and even if entirely stripped of the replaceable inner wall. Otherwise stated, the pilasters always maintain the full strength and normal stability of the outer wall. Moreover, it will be noted that in replacing the inner wall, the shelf-forming blocks are the only elements of special construction, the rest being entirely commercial fire bricks. This arrangement, therefore, makes it possible to quickly and cheaply repair and maintain the walls of furnaces. Of course, instead of the commercial fire brick, any other suitable refractory material might be used if found practicable, but the fire brick has been found by far the best for the purpose. 100 What I claim is:

1. A composite furnace wall comprising a permanent masonry outer wall having therein horizontal rows of sill-forming blocks, overlying horizontal rows of lintels and intervening pilasters, forming vertically spaced rows of horizontally spaced pockets, in combination with a high refractory replaceable masonry inner wall including shelf-forming blocks projected into and anchored within the pockets of said permanent wall. 110

2. A composite furnace wall comprising a permanent masonry outer wall having therein horizontal rows of sill-forming blocks, 120

- overlying horizontal rows of lintels and intervening pilasters, forming vertically spaced rows of horizontally spaced pockets, in combination with a replaceable masonry inner wall including shelf-forming blocks projected into the said pockets, and key blocks filling the space between the tops of said shelf-forming blocks and the tops of said pockets and anchoring said shelf-forming tiles within said pockets. 5
3. The structure defined in claim 1 in which said shelf-forming tiles have interlocking engagement with the sill blocks of said permanent wall. 10
15. 4. The structure defined in claim 2 in which said sill blocks and shelf-forming blocks have interlocking ledges whereby they are held positively interlocked by said key blocks.
20. 5. The structure defined in claim 1 in which the outer portion of said permanent wall is made up of common bricks and the inner surface thereof including said sill blocks, lintels and pilasters are of high refractory non-metallic material. 25
6. The structure defined in claim 2 in which said key blocks project into the brick work of said replaceable wall. 30
7. The structure defined in claim 2 in which said key blocks are tapered so that they may be forced tightly to position. 35
8. The structure defined in claim 2 in which said key blocks are tapered and said lintels are beveled to fit the taper of said key blocks. 40
9. The structure defined in claim 1 in which said shelf-forming blocks are ar- ranged in groups within said pockets and said groups are spaced by said pilasters, the space between the projecting portions of said shelf-forming blocks being filled in by fire brick. 45
10. The structure defined in claim 9 in which said shelf-forming tiles have approximately the cross-section of commercial fire bricks. 50
11. The structure defined in claim 9 in which said sill-forming blocks and shelf-forming blocks have interlocking ledges normally and positively anchoring said shelf-forming blocks within the pockets of the permanent wall. 55
12. The structure defined in claim 1 in which said sill-forming blocks and lintels form continuous courses, and said pilasters rest upon the continuous sill thus formed and support the lintels. 60
13. The structure defined in claim 1 in which said sill-forming blocks and lintels are built into the masonry of said permanent wall beyond the backs of the pockets formed thereby and by said pilasters. 65
14. The structure defined in claim 2 in which said sill-forming blocks and lintels are built into the masonry of said permanent wall beyond the backs of the pockets formed thereby and by said pilasters. 70
15. The structure defined in claim 2 in which said shelf-forming blocks and key blocks have approximately the cross-section of commercial fire bricks. 75

In testimony whereof I affix my signature.

MICHAEL LIPTAK.
